Atty.

UNITED STATES PATENT OFFICE

VICTOR NEWREN, OF CHICAGO, ILLINOIS

DOOR HOLDER

Application filed August 6, 1928. Serial No. 297,637.

My invention relates to a door holder.

Particularly, the invention relates to a device of this kind for use on any kind of swinging door, such for example, as a garage door. The holder functions automatically when the door has been swung open to a predetermined angle to lock the door in such open position, so that the same may not accidentally be closed as by a sudden gust of wind. Obviously, if such a door is not held open, it might very easily be damaged by the vehicle entering or leaving the garage. A simple trip member is also included in the holder to unlatch the same so that the door may be closed.

The primary object of the invention is to provide an improved and simplified door holder for doors of the swinging type, so that the same may be cheap to produce and will lend itself readily for use on standard doors without altering the structure thereof. Another object is to provide an improved unlatching device for the holder to enable the door to be closed. Other objects will be apparent as the disclosure of the invention proceeds.

These objects are achieved by this invention which briefly comprises in combination with a swinging door, a holder pivotally mounted thereon and having an enlarged head at the end thereof remote from the door slidable in a slotted keeper mounted in the door opening frame. When the door has been opened to a predetermined angle the enlarged head on the holder drops by gravity out of the slot in the keeper to lock the door against accidental closing. An unlatching device to release the holder is also provided.

In the accompanying sheet of drawings illustrating a practicable embodiment of the improved door holder of this invention:

Figure 1 is an end elevational view of the holder in the position it assumes when holding the door open;

Figure 2 is a top plan view of the same position of the parts as seen along section line 2-2 of Figure 1;

Figure 3 is a top plan view of the holder in folded position as when the door is closed;

Figure 4 is a front elevational view, partly

in section, showing the slotted keeper and how it cooperates with the holder knob; and,

Figure 5 is an end sectional view of the unlatching device, as seen along the line 5-5 of Figure 1, looking in the direction of the arrows.

A door opening is defined by a top frame member 10 and an end frame member 11 the latter carrying the usual hinge 12 for mounting a door 13 for swinging movement.

The keeper of this invention comprises a channeled member 14 secured by bolts 15 to the top frame member 10, said keeper having a long slot 16 in its bottom terminating in an enlarged hole 17. This channel fixture is very simple and is mounted in the door frame without altering the standard door structure in any way.

The holder comprises an arm 18 having at one end an upturned neck 19, head 20, and stop 21, the neck 19 adapted to ride in the slot 16 of the keeper. The opposite end of the holder arm 18 is detachably connected by a pin 22 between two spaced ears 23 on a disk 24. The ears 23 are continuations of strengthening flanges 25 on the disk. The disk is formed with an arm extension 26 and is pivotally mounted by means of a bolt 27 on a cap or bracket 28 secured in any approved manner to the door 13. A pull chain 29 and handle 30 are connected to the end of the lever arm 26 as shown.

To explain the operation of the door holder it is to be assumed that it is desired to open the door 13 which is closed as indicated in Figure 3. In this position the holder is, of course, inactive. The operator now swings open the door, which causes the neck 19 to slide from its position at the left in Figure 4 to its position at the end of the slot at the right in Figure 4 when the door has swung to a predetermined open position. The head 20 is now in register with the enlarged opening 17 and as a result the head drops by gravity into said enlarged opening. The stop 21 limits the drop of the head as will be understood. As the neck 19 cannot now ride back into the slot 16 the door is positively held open.

When it is desired to close the door, the user pulls on the chain 29 by grasping the

handle 30 which pivots the arm 26 to rock the disk 24 thus raising the arm 18 to cause the head 20 to move up so that the neck 19 is once more enabled to ride in the slot 16. The 5 arm 18 now folds up as the door is swung shut and again assumes the position illustrated in Figure 3.

From this detailed description it must now be appreciated that an improved door holder 10 structure has been provided which achieves all of the desirable objects of the invention heretofore recited.

It is the intention to cover all such immaterial changes and departures from the illustrative embodiment described, as do not depart from the spirit and scope of the invention as is indicated in the subjoined claims.

What I claim is:

1. A door holder for a swinging door in a 20 door frame, the holder comprising an arm pivotally carried on the door, said arm having an upturned neck terminating in an enlarged head, a keeper comprising a channeled member adapted to be secured to the door 25 frame having a slot therein in its bottom side terminating in an enlarged opening, said neck riding in the slot as the door is opened and the head dropping vertically into the enlarged opening when the door has fully 30 opened to maintain the door in such open position.

2. A door holder for a swinging door in a 35 door frame, the holder comprising an arm pivotally carried on the door, said arm having an upturned neck terminating in an enlarged head, a keeper comprising a member having a slot therein terminating in an enlarged opening, said neck riding in the slot as the door is opened and the head dropping 40 into the enlarged opening when the door has fully opened to maintain the door in such open position, and means on the door for swinging the arm upwardly to engage the neck with the slot to enable the door to be closed.

3. A door holder for a swinging door in a 50 door frame, the holder comprising an arm pivotally carried on the door, said arm having an upturned neck terminating in an enlarged head, a keeper comprising a member having a slot therein terminating in an enlarged opening, said neck riding in the slot as the door is opened and the head dropping 55 into the enlarged opening when the door has fully opened to maintain the door in such open position, and a stop included in the head to limit the dropping movement of the head.

4. A door holder for a swinging door in a 60 door frame, the holder comprising an arm pivotally carried on the door, said arm having an upturned neck terminating in an enlarged head, a keeper comprising a member having a slot therein terminating in an enlarged opening, said neck riding in the slot as 65 the door is opened and the head dropping

into the enlarged opening when the door has fully opened to maintain the door in such open position, means for pivoting the arm upwardly to reengage the neck in the slot, said means comprising a lever pivoted on the door, and means detachably connecting an 70 end of the lever to the arm.

5. A door holder for a swinging door in a 75 door frame, the holder comprising an arm pivotally carried on the door, said arm having an upturned neck terminating in an enlarged head, a keeper comprising a member having a slot therein terminating in an enlarged opening, said neck riding in the slot as the door is opened and the head dropping 80 into the enlarged opening when the door has fully opened to maintain the door in such open position, means for pivoting the arm upwardly to reengage the neck in the slot, said means comprising a disk rockably 85 mounted on the door and having strengthening flanges terminating in spaced ears, means connecting the holder arm between the spaced ears, and means for rocking the disk.

6. A door holder for a swinging door in a 90 door frame, the holder comprising an arm pivotally carried on the door, said arm having an upturned neck terminating in an enlarged head, a keeper comprising a channeled member adapted to be secured in the door 95 frame and having in its bottom side an elongated slot with an enlarged opening at one end of the slot, the slot forming a track for the holder neck, the enlarged opening forming a lock when the enlarged head drops vertically thereinto, and rocker means on the door connected with the arm to release the holder head from the keeper slot enlargement for closing the door.

Chicago, Illinois, August 3rd, 1928.
